US00D953521S

(12) **United States Design Patent** (10) **Patent No.:** **US D953,521 S**
(45) **Date of Patent:** **** May 31, 2022**

(54) **ORAL IRRIGATOR**

(71) Applicant: **Colgate-Palmolive Company**, New York, NY (US)

(72) Inventors: **Jiang Zhou**, Yangzhou (CN); **Yanmei Ji**, Jiangsu (CN); **Fan Gang Xie**, Shanghai (CN); **Bo Zhang**, Yangzhou (CN)

(73) Assignee: **Colgate-Palmolive Company**, New York, NY (US)

(**) Term: **15 Years**

(21) Appl. No.: **29/801,325**

(22) Filed: **Jul. 28, 2021**

Related U.S. Application Data

(62) Division of application No. 29/704,763, filed on Sep. 6, 2019, now Pat. No. Des. 929,574.

(57) **CLAIM**

The ornamental design for an oral irrigator, as shown and described.

DESCRIPTION

FIG. 1 is a front perspective view of an oral irrigator showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings illustrate portions of the oral irrigator that form no part of the claimed design.

1 Claim, 7 Drawing Sheets
